J. HAHN.
DEEP WELL PUMP.
APPLICATION FILED SEPT. 8, 1908.

993,520.

Patented May 30, 1911.

UNITED STATES PATENT OFFICE.

JOHN HAHN, OF LOS ANGELES, CALIFORNIA.

DEEP-WELL PUMP.

993,520.

Specification of Letters Patent. Patented May 30, 1911.

Application filed September 8, 1908. Serial No. 452,151.

To all whom it may concern:

Be it known that I, JOHN HAHN, a citizen of the United States, residing at 716½ East Twelfth street, Los Angeles, in the county 5 of Los Angeles and State of California, have invented new and useful Improvements in Deep-Well Pumps, of which the following is a specification.

An object of this invention is to make 10 provision for increased speed of stroke and increased delivery of liquid at each stroke. This is accomplished by providing novel means for separating from the liquid before it reaches the standing-valve, gas or air contained in such liquid, so that the same will 15 not operate to prevent rapid seating of the valves of the pump. By this arrangement the valves are allowed to seat suddenly, and the pump operates to discharge liquid that 20 is more free from bubbles of air or gas than with former pumps. In this way much loss of efficiency from back flow of liquid through the valve-seats, or from occupation 25 of space in the tubing by the air or gas, and also from the slowness of stroke heretofore necessary, is avoided. Any air or gas which reaches the working-barrel of the pump is liable to cause an emulsion of the oil under 30 the action of the piston, and the production of such emulsion will be reduced in the ratio in which the elimination of the air is effected.

An object of the invention is to avoid producing such emulsion.

Another object is to provide a cheaper and 35 simpler construction by which the liquid is prevented from flowing back around the lower part of the cage. This is effected by tapering the lower end of the cage itself, 40 and seating the taper portion in a seat prepared therefor. The taper of the lower end of the standing valve cage and the seat therefor is very slight and the tapered portion is elongate, so that when the standing 45 valve cage is driven into its seat the joint will be hermetically sealed without the use of leather cups or any other form of extension from the body of the standing valve cage and in this manner the passage for 50 liquid inside the valve can be made of the maximum size and all the advantages of the packing heretofore used may be secured.

Another object is greater economy in replacing worn parts. This is effected by 55 providing two couplings, one connected with the pump-tubing, and the other with the

anchor or suction pipe, connecting said couplings by a nipple, and providing one or more detachable liner-sections which are held in place by and between the couplings 60 and constitute the working-barrel of the pump. By this means, when the working-barrel becomes worn it is only necessary to detach the nipple from one of the couplings then remove the lining or the worn section 65 thereof, and replace it with new. In order to minimize the length of lining which must be replaced at any time because of wear, a plurality of sections may be employed, care being taken in constructing the pump that a 70 single section shall be made to extend only for that length subject to maximum wear, while another section may be made to extend along the portion subject to another degree of wear, and so on with each section, so that 75 the section most subject to wear may be replaced independently of those sections less subject to wear, thus leaving the latter sections to be further worn and afterward removed and replaced, and so on. In this 80 connection the invention consists in the construction of the sectional liners with spigot joints whereby the removal of any section and replacing the same with new may be accomplished at minimum expense of time, 85 labor and material.

Another object is to provide a construction whereby the standing-valve cage is detachably locked in its seat.

Another object is to improve the construction of valve-cages so as to afford a hold for fishing-tools, and also to provide increased strength between the sides of the cages and the pin or socket by which the same is to be connected with the pump-rod or other attachment for lifting the cage. 90

The invention may be applied in different forms, and I do not limit the same to any specific form of construction.

The accompanying drawings illustrate the 100 invention in a form I at present deem most desirable.

Figure 1 is a fragmental, vertical section of a pump embodying this invention and located in a well-casing. Portions between 105 the valve-cages are broken away to contract the view. Fig. 2 is a fragmental, sectional detail of the standing-valve cage and the parts near the same. Fig. 3 is a section on line x^3 , Figs. 1 and 2. Fig. 4 is a section on line x^4 , Figs. 1 and 2. Fig. 5 is an elevation 110 of the locking bushing that holds the cage

extension in place. Fig. 6 is an axial section of said bushing. Fig. 7 is a detail of the spigot joint.

1 is the usual well-casing perforated at 2 to admit oil or water from the earth's strata to the pump.

3 is the usual pump-tubing through which the usual sucker-rod, not shown, passes for connection with the working valve-cage 4 10 with which the usual piston 5 is connected in the usual manner.

6 is the usual standing-valve, and 7 a standing-valve cage. The pump is provided below the standing-valve with an air or gas 15 trap. In the drawing said trap is in the form of a chamber 8 between an imperforate portion 9 of the suction-pipe 10 and a conduit 11 adapted to direct liquid to the standing-valve; said conduit being provided with 20 an inlet formed by orifices 12, 13, and having an imperforate portion 14 above such inlet.

The suction-pipe 10 has an inlet formed of numerous perforations 15 through which the liquid may flow to the conduit, said suction-pipe forming a chamber outside and around such conduit to intercept air or gas on its way to the conduit; an outlet 16 being provided for air or gas from the chamber below the standing-valve. The upper part 25 of the conduit 11 is provided with an outlet 17 to communicate with the outlet 16 so that air or gas which may find its way into the conduit 11 may escape to the chamber and thence through the outlets.

35 The principle upon which the air or gas is intercepted and separated from the liquid, is that the liquid must flow across the intervening space between the suction-pipe 10 and the conduit 11, and during the passage 40 of the liquid across such space the air or gas will rise from the liquid, thus becoming entrapped between the imperforate portion 14 of the conduit and the imperforate portion 9 of the suction-pipe, and as the air or gas

45 passes through the inlet orifices 12, the air that has not escaped into the chamber 8 will rise along the imperforate wall 14 of the conduit and will ascend until it escapes through the outlets 17 and 16. The outlet 50 orifices 17 extending through the walls of the conduit are comparatively small, and the liquid which supplies the vacuum caused by the upward stroke of the piston, flows into the conduit below the imperforate portion 14.

55 The orifice in the valve-seat 18 is of less diameter than the interior diameter of the conduit 11, and is centrally arranged so that the tendency is for the liquid to flow centrally up through the conduit 11, whereby the air or 60 gas may become more readily separated from the liquid. The conduit 11 forms a downward extension of the valve-cage 7, being screwed into said valve-cage, as shown at 19.

The lower end of the valve-cage is a spigot 65 being nearly cylindrical and very slightly

tapered, as shown at 20. The novelty of the taper portion of the valve cage and its seat consists in the very elongate and slight taper, so that the same is in the form of a spigot joint. The standing valve cage 7 is 70 formed of a single piece having a lower end provided with an elongate taper portion as stated, which directly seats in the spigot joint seat 27 so that a maximum opening or bore may be provided within the valve cage 75 to accommodate the liquid. A further advantage of making the standing valve cage of a single piece with an elongate taper portion 20 is that the valve cage is thus adapted to be seated in a turret lathe and turned accurately and the seat for said tapered portion may also be turned in the same manner. This method of seating and mounting standing valve cages is new and is regarded as a very important step in advance over 80 previous constructions as it positively seals the joint at the bottom of the cage without packing and allows the cage to be drawn from and replaced into the seat therefor without any destruction of packing and also without liability of pieces of the packing lodging in the tubing when the standing valve is withdrawn, and it also considerably increases the output of the well over that of 85 those supplied with pumps having such standing valve cages as were previously constructed.

90 21 is a coupling connected with the pump-tubing 3 by means of a nipple 22 and a coupling 23. Said coupling is screwed on to the nipple 22 and is provided internally with a seat 24 for a bushing 25, the upper end of which is provided with an external flange 26 to rest on the shoulder 24. Said bushing is provided at its upper end with a taper-seat 27 for the taper portion 20 of the standing-valve cage, thus forming the spigot joint between the standing-valve cage and the bushing. Said bushing fits tightly 95 in and extends downward from the coupling 21, and its inner face is inwardly bent, as shown at the inward bend or projection 28, and is in resilient engagement with the conduit 11 so as to hold the same frictionally. Such resilient engagement may be effected 100 in various ways. In the form illustrated in the drawings, the bushing 25 and the conduit 11 are both made resilient or bendable, this being done by slotting the bushing and conduit longitudinally. The slots 29 of the conduit are narrow, thus forming a number of bars 30, the outer face of each of which is outwardly bent, as shown at 31, to engage the indent faces 28. The bars 32 of the bushing are preferably more widely separated than the bars 30 of the conduit, so as to insure escape of air and gas through the slots during engagement between the bars of the conduit and those of the bushing, regardless of how the conduit may be 105 110 115 120 125 130

turned. Means are provided to hold the bushing in the seat in the coupling, the same consists of a liner 33 which may be made of one or more sections held in place between 5 the couplings 21 and 23, which are connected by the nipple 22, the same being screwed into said couplings to draw them tightly toward each other to clamp the liner against the bushing. The couplings, the nipple and 10 the liner, constitute the working-barrel of the pump, and said liner is held in place by slip-joint construction, as shown at 34 and 35. When the liner is made of two sections, as shown in Fig. 1, said sections may also be 15 united by a spigot-joint, as shown at 36, so as to be perfectly tight.

The valve-cages are provided with means for detachable connection with a pump-rod or other appliance. For this purpose 37 is a 20 threaded pin, and 38 a threaded socket in the working and standing valve-cages respectively. Below such means for detachable connection the cages are provided with outwardly extending, overhanging shoulders shown at 39, the same being in an extension 41, above the cage proper shown at 7. Said shoulders may slant inwardly and upwardly as clearly shown in Fig. 2, for engagement with the fishing-tool, not shown. 25 A web 42 is provided between the shoulders 39 to give strength and rigidity to the upward extension 41. The valve-way 43 is limited at the top by shoulders 44 and has lateral outlets 45 leading from the valve-way, and there are below and above said outlets solid walls or rings 46 and 47, the lower walls 46 forming a cylindrical bore 48 to receive the valve-seat, said bore being threaded to receive the downward extension 40 14. The solid wall above the valve-way forms the hollow upward extension 41 terminating in the threaded socket 38 and being provided below said socket with the lateral ports 49.

45 In practice, when the standing valve-cage is lowered into position its extension will seat friction-tight in the bushing, and will seat in the taper-seat and will be held therein by frictional engagement of the extension 50 with the bushing. The piston will be operated by a pump-rod in the usual way, and the suction thereof will cause the liquid to flow horizontally across the space between the suction-pipe 10 and the extension. The 55 liquid thus flows horizontally, and the air or gas will rise therefrom and accumulate around the inside wall of the suction-pipe 9 and will ascend to the outlet 16. Any air that may reach the interior of the extension 60 may flow up along the walls of such extension and may flow out through the slits or slots 29 in the extension and through slots 40 in the bushing, and thence out through the outlet 16; or, if the air reaches so high 65 as the outlet 17 the same may flow out from

thence and through the slots 40, and thence through the outlet 16.

In my copending application for patent Serial No. 480,787, filed March 1, 1909, I have shown the combination with the pump 70 tubing of a working barrel composed of sections that are united inside the pump tubing by slightly tapered nearly straight elongate spigot joints in which the engaging surfaces are of considerable length and nearly 75 cylindrical, so that the sections are united inside the pump tubing by friction tight elongate spigot joints, said construction being a completion of the suggestion of the spigot joint shown at 36 herein but not 80 claimed herein for the reason that the same is more fully shown in said other application and is fully claimed therein.

I claim:

1. A pump provided below its standing-valve with a conduit to direct liquid to such valve, said conduit being provided with an inlet and having an imperforate portion above such inlet, means to form a chamber outside such conduit to intercept the air or 90 gas on its way to the conduit, an outlet being provided for air or gas from the upper part of said conduit and said chamber.

2. A pump provided below its standing-valve with a conduit to direct liquid to such 95 valve, said conduit being imperforate for a portion of its length and provided with an inlet below such portion, a pipe around such conduit, the same having an imperforate portion corresponding to that of said conduit and being provided with an inlet below such imperforate portion, pump tubing, and a coupling between the pipe and tubing, an outlet being provided through the coupling from the interior of the pipe above said imperforate portion.

3. A pump provided below its standing-valve with a conduit leading vertically to the standing-valve and provided with a lateral inlet, a pipe forming a chamber around 110 said conduit and provided with an inlet to direct liquid approximately horizontally toward the inlet of the conduit, an outlet being provided at the top of the chamber for the trapped air or gas.

4. A pump provided below its standing-valve with a conduit to direct liquid to the standing-valve, means outside said conduit to direct liquid horizontally to the conduit, and means to receive air or gas which may 120 rise from the horizontally moving liquid, an outlet being provided for such gas.

5. A pump provided with a standing-valve having a downward extension which is provided with an imperforate portion and 125 with an inlet below the imperforate portion, a pipe outside said downward extension, the same being provided with an imperforate portion corresponding with that of the downward extension, and with an inlet be- 130

low such imperforate portion to direct liquid toward the inlet of the downward extension, and a coupling connected with the pump tubing and provided with an outlet, 5 said pipe being screwed into said coupling to deliver air or gas to said outlet.

6. A pump provided with a standing-valve having a downward extension that has an imperforate portion and with an inlet below the imperforate portion and an outlet above the imperforate portion, a pipe outside said downward extension, the same being provided with an imperforate portion around that of said downward extension, 10 and with an inlet below such imperforate portion to direct liquid toward the inlet of the downward extension, and a coupling connected with the pump tubing and provided with an outlet, said pipe being 15 screwed into said coupling to deliver air or gas to said outlet.

7. A pump provided with a standing-valve cage that has a downward extension, a portion of which extension is imperforate, 25 an inlet being below said imperforate portion and a lateral outlet above said imperforate portion, a bushing forming a seat for the standing-valve cage, the same frictionally engaging said downward extension, and 30 a suction-pipe around said extension provided with an imperforate portion corresponding to that of the downward extension, and also provided below said imperforate portion with an inlet, and above such 35 portion with an outlet.

8. In a pump the combination with a suction-pipe of a coupling secured to the pipe and provided with an outlet leading from the interior of the pipe, a standing-valve cage provided with a downward extension inside the pipe, and a bushing in the coupling, the same forming a seat for the standing-valve cage and being in resilient engagement with the extension, and means to 40 hold the bushing in position.

9. A pump provided with tubing having a coupling a standing-valve cage and having a downward extension, a bushing in the coupling to seat the cage and to resiliently engage the extension.

10. In a pump provided with tubing having a coupling a standing-valve cage provided with a resilient barred extension and a bushing in the coupling to support the 45 cage and engage the bars of such extension.

11. A pump having a suction pipe and a standing valve seat and provided with a laterally perforated coupling that is connected with the suction-pipe of the pump 50 and carries the standing-valve seat, the perforations being between said pipe and said seat.

12. The combination of a suction-pipe, a coupling screwed thereto and provided with 55 a seat, a bushing seated in the seat and pro-

vided with a flange and a taper-seat, a standing-valve cage seated in the taper-seat, a liner one end of which rests on the bushing, another coupling provided with a seat in which the other end of the liner is seated, 70 and a nipple connecting the couplings.

13. The combination of a suction-pipe a coupling screwed thereto and provided with a seat, a bushing seated in the seat and provided with a flange and a seat, a standing-valve cage seated in the latter seat, a liner one end of which rests on the bushing, another coupling provided with a seat in which the other end of the liner is seated, 75 and a nipple connecting the couplings. 80

14. A valve-cage provided with a valve-way having lateral outlets, and with solid walls below and above said outlets and vertical passages inside said walls below and above said valve-way, said valve-cage being 85 also provided with a hollow upward extension above the upper solid wall, said extension being provided with lateral ports and with means above said ports for detachable connection with the pump-rod, and said upward extension being provided with outwardly extending, overhanging shoulders below said means and above said ports. 90

15. A laterally perforated coupling for connecting the suction-pipe of a pump with 95 the working-barrel so as to allow entrapped air to escape between such pipe and barrel.

16. A pump provided with a suction pipe that has an inlet formed of numerous perforations and has an imperforate portion 100 above said inlet, and is also provided at its top with an outlet for entrapped air or gas.

17. In a pump the combination with a standing valve and tubing, of a working barrel and the conduit set forth provided with 105 a perforate portion, an imperforate portion above the perforate portion and bendable bars above the perforate portion.

18. In a pump the combination with a standing valve and tubing of a working barrel and the conduit set forth provided with a perforate portion, an imperforate portion above the perforate portion and projecting bars above the perforate portion. 110

19. In a pump, a standing valve cage provided with a resilient extension and a resilient bushing to seat the cage and engage the resilient portion of the extension. 115

20. In a pump the combination with the working barrel and the pump tubing, of a 120 metallic slotted resilient conduit and means carried by the tubing held down by the working barrel and arranged outside said conduit to frictionally engage the same.

21. In a pump a metallic slotted resilient 125 conduit having an outward projection, pump tubing outside said resilient conduit, means between said tubing and conduit to engage said outward projection to frictionally retain the resilient conduit and a work- 130

ing barrel arranged to hold down said means.

22. In a pump the combination with the pump tubing and the working barrel, of a 5 metallic slotted resilient conduit; a downward extension of the working barrel around said conduit and having an inward projection, said conduit and said downward extension being in frictional engagement 10 with each other, and said downward extension being frictionally connected with the

pump tubing; and an anchor connected with the tubing forming a chamber around the conduit and downward extension.

In testimony whereof, I have hereunto set 15 my hand at Los Angeles, California, this 29th day of August 1908.

JOHN HAHN.

In presence of—

JAMES R. TOWNSEND,
M. BEULAH TOWNSEND.
